UNITED STATES PATENT OFFICE.

EDWARD M. STILES, OF MOUNT PLEASANT, IOWA, ASSIGNOR TO U. S. SLICING MACHINE COMPANY, OF CHICAGO, ILLINOIS, A CORPORATION OF ILLINOIS.

CONVEYING MECHANISM.

1,185,730.

Specification of Letters Patent.

Patented June 6, 1916.

Original application filed September 12, 1912, Serial No. 719,955. Divided and this application filed November 11, 1912. Serial No. 730,574.

To all whom it may concern:

Be it known that I, EDWARD M. STILES, a citizen of the United States, residing at Mount Pleasant, in the county of Henry and 5 State of Iowa, have invented certain new and useful Improvements in Conveying Mechanism, of which the following is a specification.

This application is a division of my application, Serial No. 719,955, filed Sept. 12, 10, 1912, and the present invention relates more specifically to improvements in conveying mechanism, particularly adapted, though not necessarily limited in its use with meat cutting mechanism, and the primary object of 15 the invention is to provide an improved simple, durable, and comparatively cheap conveying mechanism which will be effective and efficient in operation.

20 A further object is to provide an improved conveyer having means whereby the article being conveyed will be held against distortion.

Other and further objects will appear 25 from the following specification and appended claims in connection with the accompanying drawings; wherein this improved conveyer is illustrated in connection with a meat cutting machine and in which drawings;

Figure 1 is a side elevation of an improved conveyer of this class constructed in accordance with the principles of this invention, and showing the same as applied to a well 35 known type of meat cutter, the latter being partly in section. Fig. 2 is a front elevation of the construction shown in Fig. 1 and is viewed from the left of Fig. 1. Fig. 3 is a top plan view of the parts shown in Figs. 1 40 and 2. Fig. 4 is a detail horizontal sectional view taken on line 4—4, Fig. 2. Fig. 5 is a detail perspective view of the "fly" or member for transferring the slices from the receiver to the collector table or support. Fig. 45 6 is a detail sectional view on line 6—6, Fig. 4. Fig. 7 is a detail sectional view on line 7—7, Fig. 4. Fig. 8 is a detail sectional view on line 8—8, Fig. 4. Fig. 9 is a view partly in section of the fly actuating pawl.

50 In the drawings there is shown a collector support adjacent the meat cutter, adapted to receive the slices of meat as they are cut, and the conveyer serves in the nature of a re-

ceiver for receiving each individual slice of material as it is cut, to convey or carry it 55 away from the cutter. Means are also shown for transferring each slice from the receiver or conveyer to the collector support.

Referring now more particularly to the drawings, the platform of the meat holder is 60 designated generally by the reference numeral 10 and is provided with the usual uprights 11, preferably one or both of which may be pivoted to the platform as at 12, and is provided with a cross bar 13, which latter 65 may be forced down against the top of the block of meat to clamp the same firmly to the carriage. Means are also provided for moving the carriage backwardly and forwardly 70 behind the cutter 14, which latter is preferably in the form of a disk and preferably rotates during the cutting stroke so as to better sever the slice of meat from the piece. In the particular construction illustrated a hand wheel 15 serves as a source of power 75 for imparting a relative movement to the carriage and disk. However, such constructions are well known in the art and inasmuch as they form no part of the present invention, further specific description thereof is 80 not necessary.

Each time the carriage is returned to its normal position, as shown in Figs. 2 and 3, it is advanced forwardly, a predetermined distance so that the piece of meat will protrude out into the line of the cutting disk, and thus insure the severing of a given thickness of meat on the next stroke. In the particular construction illustrated, this advancing mechanism embodies a feed screw 85 16, which engages a grooved finger or projection 17 and which screw is rotated by any suitable mechanism a slight amount as the carriage is returned to its initial position, the degree of rotation of this screw being 90 regulated by suitable controlling mechanism 18, which is also well known in the art and is only illustrated and described in the present application for the purpose of showing the relation which this improved meat 95 stacker bears to a well known form of meat cutter.

The meat stacker comprises a collector support 19, which is preferably arranged so as to be adjusted upwardly and downwardly, 100 and is disposed adjacent the meat cutter. 105

The receiver, in the present form of this invention, comprises a carrier in the form of endless belts adapted to receive and transport the individual slices of meat as they are cut, away from the cutting disk.

The receiver or conveyer which constitutes the subject matter of this application, in the present form of the invention comprises spaced upright shafts 20, 21, arranged parallel with each other and mounted in suitable bearings in a suitably supported frame 22. The shafts 20 and 21 are arranged at an incline to the vertical, that is, they are tilted backwardly at their upper extremities toward the carriage and in a direction away from the cutter 14. The support or frame 22 for these shafts is preferably arranged to extend outwardly beyond the front face of the cutter 14 and in a direction transverse to the plane of rotation of the cutter. The receiver or carrier is preferably in the form of endless belts 23, having spaced teeth or spikes 24 projecting from the cutter face thereof. Any number of these endless belts 23 may be provided and they are constructed of any suitable flexible material.

Arranged on the shaft 21 and secured thereto for rotation therewith, is a pulley 25 which is provided with a series of spaced peripheral grooves spaced longitudinally of the shaft and into which the belts 23 run, one groove being provided for each of the belts. Mounted loosely upon the other shaft 20 are a series of pulleys 26 which are of a diameter less than the diameter of the pulley 25 and one of these pulleys 26 is provided for each of the belts 23, as shown more clearly in Figs. 7 and 8. The pulleys 26 are spaced longitudinally of the shaft 20 and arranged intermediate each pair of pulleys 26 is a sleeve or collar 27 and these sleeves or collars are secured to the shaft 20 so as to rotate therewith in any desired or suitable manner, such as by means of a fastening key or feather 28. The sleeves or collars 27 are also provided with spaced radially projecting prongs or teeth 29 and these prongs or teeth 29 are of a length slightly greater than the prongs or teeth 24 on the belts 23, for the purposes to be hereinafter set forth. With this construction it will be manifest that when the shaft 20 is rotated the sleeves or collars 27 and the prongs or teeth 29 will be rotated therewith, while the pulleys 26 over which the belts 23 pass will have a rotary movement with respect to the shaft 20.

Motion is imparted to one of the shafts, preferably the shaft 20, in any suitable manner from the main shaft of the machine, or the shaft to which the hand wheel 15 is connected. This is accomplished by means of a suitable shaft 30 which is geared to the main shaft 31 in any suitable manner and is provided with a gear 32 (see Figs. 1 and 2) which latter meshes with a gear 33 on an-

other shaft 34 mounted in suitable bearings 35 and this shaft 34 has in turn a gear 36 which meshes with a gear 37 on shaft 20. Secured also to the shaft 20 for rotation therewith and preferably at the upper extremity of the shaft, is a pulley 38 over which a drive belt 39 passes and this belt 39 also passes over another pulley 40 which is secured to the shaft 21 so that the motion imparted to the shaft 20 will be conveyed to the shaft 21. It will be manifest that the shaft 20 is directly driven from the main shaft of the machine and when rotated the shaft 20 will rotate the sleeves or collars 27 and also the pulley 38. As the pulley 38 is rotated, its motion will be imparted to the pulley 40 through the medium of the belt 39. The pulley 40, being secured to the shaft 21, and the pulley 25, being also secured to the shaft 21, the latter will be rotated by the shaft 21 and the rotation of this pulley 25 will impart motion to the belts 23, and as the belts are driven the pulleys 26 will rotate freely about the shaft 20. With this arrangement it will be manifest that the belts and the sleeves or collars 27 are not only rotated in the same direction, but at different rates of speed. The shaft 20 is located in close proximity to the cutter 14 and inasmuch as the prongs 29 are of a greater length than the prongs 24, the slice just as it is cut will be picked up by the prongs 29 and will be carried around to the front of the receiver or conveyer. The shaft 20 is located in close proximity to the cutter 14, and inasmuch as the prongs 29 are of a greater length than the prongs 24, the slice just as it is cut, will be picked up by the prongs 29 and will be carried around or over the curved surface to the front of the receiver or conveyer, where it will be delivered to the latter.

Unless means are provided for preventing the slice from becoming damaged, by the spreading action of the prongs on the belt with respect to each other, as they pass over the curved surface, or around the pulleys, (and which spreading action, with respect to the slice, is compensated by the prongs on the sleeves carrying the slice around the pulleys before the prongs on the belt engage the slice) and further unless provision is made for the purpose of removing or detaching the slice from the prongs or teeth 29, after the slice has passed over the curved surface, the slice would not be delivered to the conveyer 23, but would remain on the prongs 29 to be carried back and around such surface, and with the result that the slice would become torn or cut up. In order, therefore, to obviate this objection and to prevent distortion or stretching of the slice, and at the same time remove the slice from the prongs or teeth 29, a differential speed is given to the sleeves or collar 27, carrying the prongs 120

29, and the belts 23 carrying the prongs 24. To accomplish this end, the driving mechanism and pulleys are so arranged that the surface speed of the belts carrying the 5 prongs 24, is slightly greater than the surface speed of the sleeves or collars 27 carrying the prongs 29. This variation or difference of speed may be of any desired extent, but in practice it has been found that 10 good results can be obtained by permitting the belts to travel a distance of about 13 inches, while the sleeves or collars are traveling about 12 inches.

The prongs on the sleeves or collars will 15 pick up the slice first, and just as the slice is leaving the pulleys, after having passed thereover, the prongs on the belts will then engage the slice, and the belt prongs traveling at a little greater rate of speed than 20 the prongs on the sleeves or collars, will cause the slice to be deflected or drawn away from the prongs on the sleeves or collars. This will prevent damage to the slice by either set of prongs.

25 A guide 41 (see particularly Figs. 4 and 7) is provided adjacent the shaft 20, over which one run of the belts pass so as to permit the prongs 29 to become disengaged from the slice as the slice is carried away 30 from the cutter by the belts and thereby prevent injury to the slice. A shield 42 is also provided adjacent the shaft 20 and at the point where the slice is severed by the cutter and beneath which the slice as it is severed passes. The receiver thus constructed 35 and described is arranged adjacent the collector support 19 as shown more clearly in Figs. 2 and 3, and inclined away from the support, while the normal position of the 40 collector support is in front of the receiver or carrier and just beneath the lowermost belt thereof.

In order to deposit the slices on the collector support 19 so as to stack them thereon, means must be provided for removing the slice from the belts or receiver and for disengaging them from the prongs 24. Any suitable means may be provided for this purpose but a simple and efficient 50 means which has been found efficient in practice comprises what will hereinafter be designated a "fly" indicated generally by the reference numeral 43. This fly comprises a body portion having a series of 55 spaced fingers 44 and is secured or mounted upon a shaft 45 which latter is journaled in suitable bearings 46 arranged preferably at the lower edge of the receiver or carrier. The fingers 44 are spaced from each other 60 as are also the belts 23, so that one finger will stand in the space between each pair of belts as is shown more clearly in Figs. 3, 4 and 7, and the fingers are of such a length that they will terminate short of 65 the shaft 20 and also short of the guide 41.

When the fingers are in position between the belts, their outer faces will be below the extremities of the prongs 24 on the belts, (see particularly Fig. 6) so as to permit the slice to be carried by the receiver or 70 carrier over the faces of the fingers. When the slices have reached the proper position on the receiver, with respect to the collector support 19, the fly is dumped or shifted so that it will remove or lift the slice from 75 the belts and will deposit it on the collector support 19.

Any suitable means may be provided for dumping the fly, but a suitable and efficient means comprises an arm 47 which is preferably carried by the reciprocating meat carrier. This arm carries a dog 48 pivotally connected thereto and is controlled by the spring 49. The dog is what might be termed a one way dog, that is, when the carriage 80 moves in one direction it will engage an arm 50 on that shaft 45 and will yield so as to pass the arm without rocking the shaft 45. This, in the present form of the invention, occurs during the forward movement of the carriage or while the slice is being cut. When the carriage returns to its normal position, the dog 48 will engage the arm 50 on the shaft 45 and rock the latter in its bearings. This will dump the fly 85 43 so that the slice will be removed from the receiver and deposited onto the collector support. The dumping movement of the fly is in opposition to the stress of an elastic member 51 which is anchored at one 90 end to a fixed support and is connected at its other end to a projection 52 on the shaft so that after the fly has been dumped and the dog 48 has moved out of engagement with the arm 50 on the return movement of 95 the carriage, the elastic member 51 will return the fly to its normal position.

It is obvious that unless means are provided for adjusting the collector support 19 as the slices are stacked thereon, a suitable distance after each slice of meat has been deposited thereon, eventually the stack of slices would become so large that the movement of the fly would be interfered with, and the slices would not be properly 100 stacked. To overcome this difficulty, the collector support 19 is of such a construction that it may be automatically adjusted and is also preferably so arranged that this automatic adjustment will be effected 105 110 by the movement of the fly, that is, each time a slice is deposited by the fly, the movement of the fly or pressure against the support through the slice will effect this adjustment. In order to accomplish this, the 115 support 19 is carried by a number of uprights 53 movable in suitable guides, preferably by passing through holes or openings in the base 54 of the machine, and nuts or 120 collars 55 are provided on the uprights to 125 130

limit the upward movement of the support. These uprights are of any desired or suitable length, but preferably of a length that the normal position of the collector support 19 will be adjacent to the bottom of the receiver or carrier, and elastic members 56 preferably in the form of coiled springs surround the uprights and tend normally to move the support 19 to its normal position.

10 It is obvious that it would be possible to so proportion the springs or elastic members 56 that the collector support 19 would automatically or naturally retain its adjusted position by the deposit of a slice thereon and each time it is lowered by the action of the fly in depositing the slice. However, in order to insure that the support will maintain its lowered position, or the position to which it has been forced by the fly, retaining means are provided and preferably comprises a rack bar 57 which passes through a suitable guide or opening in the base 54 and a pawl 58 controlled by a spring 59 is also provided which coöperates with the teeth 57 so that each time the collector support is adjusted by the deposit of a slice thereon, the pawl 58 will yield and will then lock the support against return movement under the stress of the springs 25

30 50. In order to permit the support to return to its normal position, a tripping means, preferably in the form of a rock shaft 60 having a handle 61 secured thereto and located in a convenient position for the operator, is provided so that the pawl 58 may be lifted out of engagement with the teeth of the rack and when thus released the support 19 will be moved by the springs back to its normal position.

40 Obviously, the springs 56 must be of sufficient strength to prevent the collector support 19 from dropping of its own weight in connection with the weight of the slices and it must also be of a strength that it will 45 only move a distance substantially equal to the thickness of the slice being deposited thereon, while at the same time it should not be of such a strength that it would not be adjusted by the fly. It will be manifest that with this construction the slices will be uniformly stacked and at the same time the fly will operate as a presser not only to move the collector support 19, but also to serve as a means for packing the slices as they are stacked. Obviously, the support or frame 55 22 may be held in position in any desired or suitable manner and braces and supports may also be provided wherever it is found necessary.

60 While in the present exemplification of the invention the preferred form of construction is herein shown, it is to be understood that many changes may be made in the details of construction and arrangement of the several parts, within the scope of the

claims, and without departing from the spirit of the invention.

The term "fly" as used in the specification and claims in this case is to be considered in its broadest interpretation, that is, to mean any mechanism for lifting or dumping or even conveying the slices from the receiver or carrier and depositing them upon the collector support. Furthermore, while the entire mechanism as shown in the drawings is described herein, in detail, it is to be understood that they do not all constitute a portion of the present invention, the latter being confined to the conveyer.

What is claimed as new is:—

1. Conveying mechanism for thin flexible slices, said mechanism embodying traveling coöperating elements each having means engaging and penetrating the article being conveyed, said means operating to hold the article against distortion, and means operating said elements at different rates of speed.

2. Mechanism for conveying thin flexible articles, said mechanism embodying coöperating movable elements having means for holding against distortion the article being conveyed, said means comprising teeth on the respective elements which have engagement with and penetrate the article, and means operating said elements at different rates of speed.

3. Conveying mechanism for thin flexible articles, said mechanism embodying coöperating movable elements having means for holding against distortion the article being conveyed, said means comprising teeth on the respective elements which have engagement with and penetrate the article, and means operating said elements at different rates of speed, some of the teeth being of greater length than others of the teeth.

4. Conveying mechanism for thin flexible articles, said mechanism embodying coöperating toothed rotatable elements, having a common axis of rotation, means on the elements having simultaneous engagement with and penetrating an article to hold the latter against distortion, and means actuating the elements at different speeds of rotation and while the first said means have engagement with the article.

5. The combination of a support, a traveling conveyer adjacent the support for receiving slices of meat, a rotatable toothed element coöperating with the conveyer and traveling at a rate of speed different from the rate of speed of the speed of the conveyer, said element and conveyer having simultaneous engagement with the slice, and means for causing the toothed element to disengage the slice.

6. The combination of a support, an endless traveling toothed conveyer adjacent the support for receiving slices of meat, a ro-

5 tatable toothed element coöperating with the conveyer and traveling at a rate of speed different from the rate of speed of the conveyer, said element and conveyer having simultaneous engagement with the slice, and a guide over which a portion of the conveyer passes for causing the said element to disengage the slice.

10 7. A conveyer for thin flexible slices of meat and the like embodying a toothed carrier, a rotatable toothed element coöperating with the carrier, the teeth of the carrier and the teeth of the element having simultaneous engagement with and penetrating the slice, and means operating said element and carrier at different rates of speed.

15 8. A conveyer for thin flexible slices of meat and the like embodying a toothed carrier, a rotatable toothed element coöperating with the carrier, the teeth of the carrier and the teeth of the element having simultaneous engagement with and penetrating the slice, said element and carrier traveling in the same direction, and means operating the element and carrier at different rates of speed.

20 9. A conveyer for slices of meat and the like embodying a toothed carrier, and a rotatable toothed element coöperating with the carrier, the teeth of the carrier and the teeth of the element having simultaneous engagement with the slice, said element and carrier operating at different rates of speed, the axes of rotation of the carrier and element being inclined to the vertical.

25 35 10. A conveyer for slices of meat and the like embodying an endless toothed carrier belt, a rotatable toothed element coöperating with the carrier, the teeth of the carrier and the teeth of the element having simultaneous engagement with the slice, said element and carrier operating at different rates of speed, and a guide adjacent the said element and over which one run of the carrier passes for directing the latter away from the said element and laterally with respect to the element.

40 45 11. A conveyer for slices of meat and the like, embodying a toothed carrier, a rotatable toothed element coöperating with the carrier, the teeth of the carrier and the teeth of the element having simultaneous engagement with the slice, said element and carrier operating at different rates of speed, the teeth on the carrier and on the said element being of different length so that one set will project beyond the other, and means for causing the teeth on one to disengage the slice while the other teeth remain in engagement with the slice.

50 55 60 65 12. A conveyer for slices of meat and the like embodying a carrier, a rotatable element coöperating with the carrier and engaging the slice simultaneously with the carrier, and means on the carrier and element for holding the slice against distortion, during a portion

of the time that the slice is being conveyed by the carrier.

13. A conveyer for thin flexible slices of meat and the like embodying a toothed carrier, a rotatable toothed element coöperating with the carrier, the teeth of the carrier and the teeth of the element having simultaneous engagement with and penetrating the slice, means operating said element and carrier at different rates of speed, and a shield coöperating with the teeth.

14. Conveying mechanism for flexible slices, said mechanism embodying a toothed conveyer element movable over a curved surface, means adjacent such curved surface and coöperating with the said conveyer element to receive the slice and convey it over such surface out of contact with the said element, the said means presenting the slice as it passes from such surface to the conveyer element.

15. Conveying mechanism for flexible slices, said mechanism embodying a toothed conveyer element movable over a curved surface, means adjacent such curved surface and coöperating with the said conveyer element to receive the slice and convey it over such surface out of contact with the said element, the said means presenting the slice as it passes from such surface to the conveyer element, the said means operating to compensate the spreading action of the conveyer element teeth during their passage over such surface.

16. Conveying mechanism for flexible slices, said mechanism embodying a toothed conveyer element movable over a curved surface, a rotatable toothed element adjacent such surface, said rotatable element receiving the slice and conveying it over said surface out of contact with the teeth of the said conveyer element to compensate the spreading action of the teeth of the latter, the teeth of the rotatable element passing out of engagement with the slice as the conveyer element teeth pass into engagement therewith.

17. Conveying mechanism for flexible slices, said mechanism embodying a toothed conveyer element movable over a curved surface, a rotatable toothed element adjacent such surface, said rotatable element receiving the slice and conveying it over said surface out of contact with the teeth of the said conveyer element to compensate the spreading action of the teeth of the latter, the teeth of the rotatable element passing out of engagement with the slice as the conveyer element teeth pass into engagement therewith, said elements rotating at different speeds.

18. Conveying mechanism for flexible slices, said mechanism embodying a toothed conveyer element movable over a curved surface, a rotatable toothed element adja-

cent such surface, said rotatable element receiving the slice and conveying it over said surface out of contact with the teeth of the said conveyer element to compensate the 5 spreading action of the teeth of the latter, the teeth of the rotatable element passing out of engagement with the slice as the conveyer element teeth pass into engagement therewith, said elements rotating at different 10 speeds and in the same direction.

19. A conveyer for flexible slices embodying a rotatable element provided with radial teeth, a traveling conveyer element movable about the axis of rotation of the 15 said rotatable element, teeth carried by the conveyer element, and being of a length less than the length of the said radial teeth, the latter teeth receiving and conveying the slice about the axis of the rotatable element, 20 out of contact with the conveyer element teeth and presenting the slice to the latter as the radial teeth move out of engagement with the slice.

20. A conveyer for flexible slices embodying a rotatable element provided with radial teeth, a traveling conveyer element movable about the axis of rotation of the said rotatable element, teeth carried by the conveyer element, and being of a length less than the 25 length of the said radial teeth, the latter teeth receiving and conveying the slice about the axis of the rotatable element, out of contact with the conveyer element teeth and presenting the slice to the latter as the radial 30 teeth move out of engagement with the slice, said elements traveling at different speeds.

21. A conveyer for flexible slices, embodying a rotatable element provided with radial teeth, a traveling conveyer element movable about the axis of rotation of the said rotatable element, teeth carried by the conveyer element, and being of a length less than the 40 length of the said radial teeth, the latter teeth receiving and conveying the slice about the axis of the rotatable element, out of contact with the conveyer element teeth and presenting the slice to the latter as the radial teeth move out of engagement with the slice, said elements traveling at different speeds, 45 some of the teeth of both elements being in engagement with the slice during its movement by the conveyer element.

22. A conveyer for slices of meat and the like embodying a toothed carrier, a rotatable toothed element coöperating with the carrier, the teeth of the carrier and the teeth of the element having simultaneous engagement with the slice at one portion of the travel of the slice, said element and carrier 55 operating at different rates of speed, the teeth on the element being rigid with respect to each other and of a greater length than the teeth on the carrier to project beyond the latter, and a pulley over which the carrier travels, said element operating to carry the 60

slice over the pulley out of contact with the carrier teeth, to overcome the effects of the spreading action of the teeth upon the slice.

23. A conveyer for slices of meat and the like embodying a toothed carrier, a rotatable toothed element coöperating with the carrier, the teeth of the carrier and the teeth of the element having simultaneous engagement with the slice at one portion of the travel of the slice, said element and carrier 70 operating at different rates of speed, the teeth on the element being rigid with respect to each other and of a greater length than the teeth on the carrier to project beyond the latter, a pulley over which the carrier 75 travels, said element operating to carry the slice over the pulley out of contact with the carrier teeth, to overcome the effects of the spreading action of the teeth upon the slice, and provisions for causing the teeth of the 80 said element to move out of contact with the slice while the carrier teeth are in engagement therewith.

24. A conveyer for slices of meat and the like embodying a rotatable toothed element, 90 a traveling toothed carrier movable about the axis of rotation of the element, the teeth of the element being of a greater length than the teeth of the carrier to project therebeyond, said carrier and element rotating at 95 different speeds, and provisions whereby the teeth of the said element will be retracted as the carrier teeth move into engagement with the slice.

25. Conveying mechanism for conveying 100 flexible slices over a curved surface and then in a substantially straight line, said mechanism embodying traveling teeth or prongs arranged along the path of movement of the slice, and with a plurality of which teeth 105 the slice has simultaneous engagement after it is received by the said mechanism.

26. Conveying mechanism for conveying flexible slices over a curved surface and then in a substantially straight line, said mechanism embodying traveling teeth or prongs arranged along the path of movement of the slice, and with a plurality of which teeth the slice has simultaneous engagement after it is received by the said mechanism, and during 115 its passage over the said curved surface.

27. Conveying mechanism for conveying flexible slices over a curved surface and then in a substantially straight line, said mechanism embodying traveling teeth or prongs arranged along the path of movement of the slice, and with a plurality of which teeth the slice has simultaneous engagement after it is received by the said mechanism, the 120 said teeth being so disposed and with respect to the said curved surface, as to move the slices over such surface without distorting the slice.

28. Conveying mechanism for conveying 125 flexible slices, over a curved surface and then

in a substantially straight line, said mechanism embodying traveling teeth or prongs arranged along the path of movement of the slice, and with a plurality of which teeth the slice has simultaneous engagement after it is received by the said mechanism, the said teeth being so disposed and with respect to the said curved surface, as to move the slices over such surface without distorting the slice, and while the teeth are in engagement with the slice.

29. Conveying mechanism for conveying flexible slices over a curved surface, said mechanism embodying traveling teeth or prongs movable along the path of movement

of the slices, and with a plurality of which teeth the slice has simultaneous engagement after it is received by the said mechanism, the said teeth being so disposed and with respect to the said curved surface, as to move 20 the slices over such surface without distorting the slice.

In testimony whereof I have signed my name to this specification, in the presence of two subscribing witnesses, on this 6th day 25 of November A. D. 1912.

EDWARD M. STILES.
